CABINET

Frank J. Matchette, New York, N. Y., assignor to
The Servidor Company, New York, N. Y., a corporation of Delaware

Application August 12, 1932, Serial No. 628,513

9 Claims. (Cl. 312—152)

This invention relates to a cabinet adapted to be pivotally attached to the door of a dining room or dinette to form therewith a convenience closet for storing service articles and supplies in an orderly manner.

One-room apartments are frequently provided with a kitchenette which is formed as a cabinet closed by a door or a pair of doors. Cabinets of this type contain the refrigerator, stove, sink, work table and storage shelves. However the amount of space available for storage is somewhat limited. It frequently happens that the doors by which the kitchenette is closed when not in use, are spaced several inches from the front edges of the above devices. The cabinet of the present invention is particularly adaptable in a situation of this kind, inasmuch as it can be mounted upon the door to occupy what is otherwise waste space when the doors are closed.

The cabinet of the instant invention may also be mounted upon a dining room or dinette door to afford additional buffet space in the dining room. In either case the cabinet of the instant invention affords a convenient storage space for storing dishes, glasses, beverages, bottle openers, and the like.

Broadly speaking, the instant invention is an improvement on my copending application, Serial No. 485,873, filed October 2, 1930.

In its preferred form the cabinet of my invention comprises a structure having an open face adapted to be registered with the door. The structure is adapted to be mounted to swing either to the left or right on the door, and is provided with a suitable latch for retaining it thereagainst.

The inside of the cabinet is equipped with a plurality of shelves on one of which is hinged a table structure. This table is generally triangular in shape and normally hangs in a vertical position within the cabinet. The table can be elevated into a horizontal position across the face of the door when the cabinet is opened away therefrom, and I have provided a strap pivotally attached to the table and adapted to engage one of the shelves in the cabinet to retain the table in a horizontal position. Hooks are also provided within the cabinet.

Inasmuch as it may be desirable to have the buffet under lock and key, I have provided a latch which is equipped with a key lock that is operable to prevent surreptitious operation of the latch.

My invention will be best understood by reference to the accompanying drawings in which a preferred embodiment of it is shown by way of example and in which:

Figure 1 is an elevational view of the cabinet mounted upon a door and opened away therefrom;

Figure 2 is a cross sectional view of the cabinet taken along the line 2—2 of Figure 1 looking in the direction of the arrows;

Figure 3 is a cross sectional view taken substantially along the line 3—3 of Figure 2;

Figure 4 is a fragmentary elevational view taken along the line 2—2 of Figure 1 and drawn to an enlarged scale to show the details of the shelf structure;

Figure 5 is a cross sectional view along the line 5—5 of Figure 4 looking in the direction of the arrows;

Figure 6 is a cross sectional view taken along the line 6—6 of Figure 4 looking in the direction of the arrow;

Figure 7 is a perspective view of the table structure; and

Figure 8 is a perspective view of the combined lock and latch structure.

Referring now to the drawings in more detail, the door, indicated generally at 1, and upon which the cabinet of my invention is adapted to be mounted, comprises, side stiles 2 and 3, which are connected together by suitable top and bottom rails 4 to form a frame for the panel or panels 5.

The shell or body structure of the cabinet of my invention comprises angle members 6 which have one leg adapted to engage the stiles of the door, and have another leg adapted to be disposed at right angles to the door. The stile engaging legs of the structure are pierced with a plurality of holes 7 through which mounting screws are projected to mount the hinge 8 thereupon. Both angle members 6 are so pierced so that the hinges may be mounted upon either one of them to thereby permit mounting hinges either upon the right or the left side of the cabinet.

Formed integrally with the free edges of the second ones of the legs of said angles, are side pieces 10, disposed at an acute angle to the door and extending towards the central portion thereof. The free edges of these side pieces 10 are formed integral with the planar front panel member 11, which is disposed substantially parallel to the panel 5 of the door.

A top plate 12 is registered with the angles 6, side pieces 10 and panel 11, and contains flanges by which it is fixed thereto, preferably by welding. This top plate 12 is pierced with two holes 14, one located near each end of the plate. These holes are adapted to receive a pin by which a suitable

door stop is fixed to the cabinet to limit the movement of the cabinet with respect to the door. A similar bottom plate 15, having flanges 16 registered with the angles, side pieces and panel 5 of the door is fixed in the opposite end of the cabinet to close the same. The bottom 15 is not ordinarily provided with holes, since the door stop is mounted at the top rather than at the bottom of the cabinet.

10 The precise dimensions of the structure thus formed will be varied to fit various sizes of doors. In all instances, however, the angles 6 will be spaced far enough apart to permit them to overhang the side stiles of the door, and the cabinet 15 structure will be long enough to overhang the top and bottom rails of the door. Preferably, the cabinet is approximately seven inches narrower than the width of the door, so that there is a margin of three and one-half inches upon each 20 side of the cabinet when it is secured to the door. This margin is ample to permit the door knob to be operated with ease, particularly since the edges of the cabinet adjacent the door knob are tapered to increase the working room. The 25 length of the cabinet is preferably several inches shorter than the door, so that, when the cabinet is installed upon the door it is disposed at some distance above the floor of the room. This permits the floor under the cabinet to be easily 30 cleaned with an ordinary broom or mop.

35 The thickness of the cabinet is preferably approximately the same as the width or thickness of the door frame. Thus when the cabinet is mounted on the side of the door swinging into the frame when the door is closed, the cabinet fits 40 within the door frame and occupies only what is otherwise waste space. In certain instances, where a door is mounted to swing through ninety degrees into parallel relation with a wall, having the cabinet of a thickness equal to the thickness 45 of the frame of the door permits the door to be fully opened before the cabinet strikes against the wall. The tapered edges of the cabinet, in either event, permit its installation upon the door and operation thereon without striking against the door frame.

50 In the embodiment shown sheet metal is used in the construction of this shell or body of the cabinet. While this material is preferable, because of its great strength and relatively low cost, I am not to be limited to cabinets constructed in this manner, as I contemplate employing wood, or the composition building material commercially known as "Presswood". 55 When composed of any one of these materials the cabinet may be finished to match the finish of the room in which it is installed, or to match the door upon which it is mounted.

60 Within the cabinet, and in the upper part thereof, I have placed two shelves 17 each of which is generally Z-shaped and provided with a downwardly depending flange 18 fitted against the front panel 11 of the cabinet and fixed thereto, preferably by welding. An upwardly extending flange 19 along the front edge of the shelf 17 is registered with the angle 6 of the cabinet and fixed thereto, preferably by welding. Shelves 17 are spaced from the top of the cabinet and from each other sufficiently far to receive 65 tall articles such as bottles, plates, and the like. Guard bars 20 are disposed above the shelves and fixed to the angles 6, to prevent such tall articles from falling off of the shelf.

70 A plurality of hooks 18' are fixed to the leg 75 18 of each one of the shelves 17, preferably by

welding. These hooks are spaced to permit hanging tea cups, bottle openers, mixers, and the like thereon.

At the approximate center of the cabinet I have located another shelf 21 which is constructed 5 in the foregoing manner. A pair of hinges 22 are welded to the underside of this shelf at the front edge thereof, these hinges also being fastened to a table structure, indicated generally at 23, to pivotally mount this structure upon the 10 shelf.

The table comprises a generally triangular plate 24 bordered on all sides by downwardly depending flanges 25. A reinforcing flange 26 is fitted over the flange 25 with one of its legs 27 15 extending inwardly of the table and the other leg 28 extending along the outer edge of the table and a short distance beyond the top thereof. A cover 29, preferably linoleum or a similar composition, is fitted on the top of the table 24 20 and within the margin defined by the edges of the reinforcing flange 26. The cover is securely fixed in place in any preferred manner such as by cementing.

Upon the inside edge of the flange 25 I have 25 fixed a plurality of reinforcing plates 30 which are pierced and tapped, as shown at 31, to receive screws 32 by which the table is secured to the hinges 32. As will be seen in Figure 7, two of the sides of the table are of the same length and 30 disposed at right angles to each other. Each of these sides is provided with two reinforcing plates 30 and two sets of tapped holes 31 so that the hinges may be attached to either one of these sides. This arrangement permits mounting the 35 table correctly for right or left swinging movement of the cabinet upon the door.

Centrally located in these two sides of the table are fixed reinforcing plates 32 which are drilled and tapped at 33 to receive the collared 40 screw 34 by which a supporting strap 35 is pivotally mounted upon the table. The free end of this strap is formed as a hook 36 which is adapted to be registered with the flange 19 of the bottom one of the shelves 17, to support the table in a 45 horizontal position.

A spring clip 38 is attached to the table by a screw 37, threaded into the innermost one of the tapped holes 31 in the plate 30 located at the free end of the side of the table to which the brace 50 35 is attached. When the table is moved upon its hinges into a vertical position, in which it is shown in dotted lines in Figures 1 and 2, the brace strap 35 is registered with the clip 38 and securely held with respect to the table. This 55 prevents the strap from banging against the cabinet as the door is opened and closed.

Beneath the table supporting shelf 21 I have placed shelves 40, which are made narrower than the depth of the cabinet to provide a space in 60 which the table is disposed when in a vertical position. These shelves 40 are generally Z-shaped and have one leg fixed to the panel 11 as before. However, inasmuch as the shelves are narrow, the front flange of them does not engage the angles 6 and consequently I have provided reinforced brackets 41 fixed to the shelf and panel engaging leg thereof, to brace the shelf. The lower one of the shelves 40 is provided with a guard bar 42. As will be seen in Figure 3, this bar 42 is 65 generally U-shaped and is secured to the side pieces 10 of the panel, rather than to the angle 6 as are the guard bars 20.

A guard bar 43 is fixed to the angles 6 a short 70 distance above the bottom 15 of the cabinet to 75

permit using the bottom plate as a shelf for receiving tall articles.

The combined latch and lock comprises a lock mounting escutcheon 45 which is generally L-shaped and is pierced to receive the key lock mechanism 46. A latch mounting escutcheon 47 registers with one leg of the lock escutcheon, and is held thereagainst by screws 48, which also serve to mount the lock upon the cabinet. Movable member 49 of the latch mechanism is pivotally mounted upon the escutcheon 47 by suitable pivot means 50 and urged into its normal position by a spring 51 which surrounds the pivot pin.

The movable member includes hook shaped arms 52 and a handle 53 by which the member is rotated on its pivot to disengage the hooks 52 from the striker plate 54 mounted upon the door.

An operation of the lock 46 by manipulation of the key raises the bolt 55 of this lock into engagement with the back side of one of the hooks 52. This blocks the movable member of the latch and prevents rotation of the same. The cabinet is thus locked by the key lock.

Movement of the cabinet with respect to the door 1 is limited by a door stop comprising levers 60 and 61 which are pivotally connected together at 62. Lever 60 is pivotally mounted upon an escutcheon 63 fixed to the door, and lever 61 is pivotally connected to the cabinet by a pin 64. A boss 65 on the end of lever 60 strikes against the edge of lever 61 to prevent the pivots from moving into a straight line as the cabinet is opened away from the door. The engagement of the boss 65 with the lever 61 limits the movement of the cabinet.

Having thus shown and described my invention, what I consider new and desire to have protected by Letters Patent is pointed out in the appended claims.

40. What is claimed is:

1. A cabinet adapted to be mounted on a conventional door for swinging movement with respect thereto, comprising an open face structure of appreciable depth, a plurality of shelves fixed in the upper part of said cabinet, guard bars fixed above said shelves to retain tall articles thereon, a generally triangular table, hinges securing said table to one of said shelves and normally disposing the same in a vertical position within said cabinet, said table being rotatable on said hinges into a horizontal position with respect to said cabinet, a strap pivotally attached to said table and having a hook formed thereon, and means on one of said shelves engageable with said hook to retain the table in said horizontal position, a plurality of narrow shelves fixed in said cabinet below said table, and a guard bar fixed in said cabinet above the bottom plate thereof to retain articles thereon.

60. 2. A buffet cabinet comprising a generally rectangular structure having an open face and having flanges extending inwardly of said open face, said flanges being pierced to permit mounting hinges on either side of the cabinet, the edges of said cabinet adjacent said flanges being pierced with holes to permit mounting a latch on either side of the cabinet, a shelf fixed in the cabinet, a generally triangular symmetrical table having two equal straight sides disposed at right angles to each other, each of said sides being pierced to permit mounting hinges thereupon, whereby the table may be mounted with the third side of said table extending from either side of the cabinet, hinges fixed to said shelf and to said

table by one set of openings, and means for retaining said table in the plane of said shelf.

3. A buffet cabinet adapted to be attached to one side of a door having side stiles joined together by top and bottom rails, comprising, a pair of angle members adapted to engage the stiles of the door when the cabinet is mounted thereon, integral side pieces extending from said angle members at an acute angle to the angle members, a front panel formed integrally with said side pieces and disposed parallel to the door when said cabinet is mounted thereon, top and bottom plates fixed to said angles, side pieces, and panel and having flanges adapted to register with the top and bottom rails of the door respectively when the cabinet is mounted thereon, said stile engaging legs of said angles being pierced with holes to permit mounting hinges on either side of the cabinet, the other legs of said angles being pierced with holes to permit mounting a latch on either side of the cabinet, a shelf mounted in the cabinet, a triangular table registered with said shelf, hinges fixed to said table and to said shelf to pivotally connect the two, means comprising a strap pivotally connected to said table, and means disposed within said cabinet and engageable with said strap for holding the table in a horizontal position with respect to said cabinet.

4. A buffet cabinet adapted to be attached to one side of a door having side stiles joined together by top and bottom rails, comprising, parallel angle members joined together by integral side pieces, each disposed at an acute angle to one leg of each angle member, and a panel disposed parallel to the legs of the angles, top and bottom pieces closing said cabinet, one leg of each of said angles being adapted to be registered with the stiles of a door when the cabinet is mounted thereon, and containing a plurality of holes to permit mounting a hinge upon either one of the angles, the other legs of said angles being pierced with holes to permit mounting a latch on either side of the cabinet, a plurality of shelves fixed in said cabinet near the top thereof, guard bars fixed to said angles and disposed above said shelves to retain tall articles thereon, a plurality of hooks attached to each one of said shelves, a centrally located shelf, a table, hinges on the said table upon said centrally located shelf, a strap pivotally connected to said table and means on one of said plurality of shelves engageable with said strap to hold the table in a horizontal position, said strap being releasable from said last named means to permit the table to be dropped into a vertical position, a second plurality of shelves fixed in said cabinet below said table, said shelves being set back from the open face of the cabinet to provide a clear space into which the table fits when in a vertical position, a guard bar fixed to said side pieces and disposed above one of said latter shelves to retain tall articles thereon, and a guard bar fixed to said angles and disposed above said bottom plate to retain tall articles thereon.

5. A buffet cabinet adapted to be attached to one side of a door having stiles and top and bottom rails, comprising, a pair of angle members adapted to engage said stiles when the cabinet is mounted upon the door, integral side pieces extending from said angles at an acute angle to the angle members, a front panel formed integrally with said side pieces and disposed parallel to the door when the cabinet is mounted thereon, top and bottom plates fixed to said angles, side pieces, and panel, and having flanges adapted to

register with the top and bottom rails of the door respectively, when the cabinet is mounted thereon, the stile engaging legs of said angles being pierced with holes to permit mounting hinges on either side of the cabinet, the other legs of said angles being pierced with holes to permit mounting a latch on either side of the cabinet, a plurality of shelves fixed in said cabinet near the top thereof, guard bars fixed to said angles and disposed above said shelves to retain tall articles thereon, a plurality of hooks attached to each of one of said shelves, a shelf fixed centrally in said cabinet, a table hinged to the front edge of said shelf, said table comprising a symmetrical generally triangular plate having downwardly turned flanges, an angular edge member disposed adjacent said flanges and extending thereunder and above said plate, a composition cover fixed upon said plate and against said edge member, a strap pivotally connected to said table, means on one of said plurality of shelves engageable with said strap to hold the table horizontal, the strap being releasable from said last named means to permit the table to be dropped into a vertical position, a clip on the edge of said table for holding said strap thereagainst when the table is in a vertical position, a plurality of narrow shelves mounted in said cabinet below said table supporting shelf, a guard bar fixed to said side pieces and disposed above one of said narrow shelves to retain tall articles thereon, and a guard bar fixed to said angles and disposed above said bottom plate to retain tall articles thereon.

6. A cabinet adapted to be mounted on a conventional door for swinging movement with respect thereto, comprising an open face structure of appreciable depth, a shelf fixed in the cabinet, a generally triangular symmetrical table having two equal straight sides disposed at right angles to each other, each of said sides being pierced to permit mounting hinges thereupon, whereby the table may be mounted with the third side of said table extending from either side of the cabinet, hinges fixed to said shelf and to said table by one set of openings, and means for retaining said table in the plane of said shelf.

7. A cabinet adapted to be mounted on a conventional door for swinging movement with respect thereto, comprising an open face structure of appreciable depth, a plurality of shelves fixed in said cabinet near the top thereof, guard bars fixed to the marginal edges of said cabinet and disposed above said shelves to retain tall articles thereon, a centrally located shelf, a table, hinges on said table upon said centrally located shelf, a strap pivotally connected to said table, means on one of said plurality of shelves engageable with

said strap to hold the table in a horizontal position, said strap being releasable from said last named means to permit the table to be dropped into a vertical position, a second plurality of shelves fixed in said cabinet below said table, said shelves being set back from the open face of the cabinet to provide a clear space into which the table fits when in a vertical position, a guard bar fixed to the marginal edges of said cabinet and disposed above one of said latter shelves to retain tall articles thereon, and a guard bar disposed adjacent and above the bottom of said cabinet to retain tall articles thereon. 5 10

8. A cabinet adapted to be mounted on a conventional door for swinging movement with respect thereto, comprising an open face structure of appreciable depth, a plurality of shelves fixed in said cabinet near the top thereof, guard bars fixed to the marginal edges of said cabinet and disposed above said shelves to retain tall articles thereon, a shelf fixed centrally in said cabinet, a table hinged to the front edge of said shelf, said table comprising a symmetrical generally triangular plate having downwardly turned flanges, an angular edge member disposed adjacent said flanges and extending thereunder and above said plate, a composition cover fixed upon said plate and against said edge member, a strap pivotally connected to said table, means on one of said plurality of shelves engageable with said strap to hold the table horizontal, the strap being releasable from said last named means to permit the table to be dropped into a vertical position, a clip on the edge of said table for holding said strap thereagainst when the table is in a vertical position, a plurality of narrow shelves mounted in said cabinet below said table supporting shelf, a guard bar fixed to the marginal edges of said cabinet and disposed above one of said narrow shelves to retain tall articles thereon, and a guard bar fixed to the marginal edges of said cabinet and disposed adjacent and above the bottom of the cabinet to retain tall articles thereon. 20 25 30 35

9. A cabinet adapted to be mounted on a conventional door for swinging movement with respect thereto, comprising an open face structure of appreciable depth, a shelf mounted in said cabinet, a table hinged to said shelf, a second shelf mounted in said cabinet in spaced relation to said first shelf, a substantially vertical flange formed on said second shelf, a strap pivotally secured to said table, and a hook on said strap engageable with said flange to retain the table in a horizontal position with respect to said cabinet. 45 50 55
